UNITED STATES PATENT OFFICE.

DAVID BELL, OF BUFFALO, NEW YORK, ASSIGNOR TO BUFFALO FOUNDRY & MACHINE COMPANY, OF BUFFALO, NEW YORK, A CORPORATION OF NEW YORK.

POWER-HAMMER.

1,260,745.

Specification of Letters Patent. Patented Mar. 26, 1918.

Application filed May 13, 1916. Serial No. 97,214.

To all whom it may concern:

Be it known that I, DAVID BELL, a citizen of the United States, residing at Buffalo, in the county of Erie and State of New York, 5 have invented new and useful Improvements in Power-Hammers, of which the following is a specification.

This invention relates to a power hammer and has for its object to so mount the hammer head that the guides for the same may be removed from the hammer head and the 10 columns or frames while the hammer head is arranged between these guides and without detaching the hammer head or necessitating lifting the same above the top of the 15 guides for this purpose as has been customary heretofore.

In the accompanying drawings:

Figure 1 is a front elevation of a power 20 hammer equipped with my improvements. Fig. 2 is a horizontal section of the same, on an enlarged scale, taken substantially on line 2—2, Fig. 1 and showing the right guide in section. Fig. 3 is a fragmentary 25 end elevation of the lower parts of the hammer.

Similar characters of reference indicate corresponding parts throughout the several views.

30 In its general organization this power hammer comprises a bed plate or base 1, two columns or side frames 2, 2 secured at their lower ends to opposite ends of the bed plate and rising therefrom, a head or cap 3 secured to the upper ends of the columns, an anvil block 4 arranged within an opening of the bed plate between the columns and provided at its upper end with an anvil 5, an anvil die 6 mounted on the upper side 35 of the anvil, a vertically movable hammer head 7 arranged between the upper parts of the columns or side frames, an engine or motor cylinder 8 mounted on the head 3, a piston 9 arranged to move vertically in this 40 cylinder and connected with the hammer head by means of a vertical piston rod 10, and a hammer head die 11 mounted on the lower end of the hammer head and adapted to coöperate with the anvil die.

45 Fluid under pressure is utilized in this example of the power hammer for raising the hammer head and also assisting gravity in depressing the same for delivering a blow against the workpiece 12 which is interposed 50 between the anvil die and hammer head die.

The pressure fluid for this purpose is controlled by means of a valve mechanism which comprises a valve chamber 13 and a vertically movable valve rod 14 which is operatively connected with the valves in the 60 valve chamber. This valve mechanism of itself forms no part of this invention and the same is therefore not shown in detail.

In hammers of this type as heretofore constructed the anvil block, hammer head 65 and the dies mounted thereon were usually so arranged that the same were in line with or parallel with the longitudinal center line of the bed plate and columns which arrangement rendered it impossible to forge or 70 hammer a workpiece if the length of the workpiece exceeded the length of the gap or space between the lower parts of the columns and therefore limited the capacity of the hammer accordingly. In this improved 75 hammer the anvil block, hammer head and the dies and other parts associated therewith are arranged at an angle relative to the center line of the bed plate and the columns, preferably at an angle of 20 degrees 80 with reference to this line, as shown in Fig. 2. By this means a workpiece, as shown by dotted lines in Figs. 1 and 2 and having a length greater than the distance between the lower parts of the columns can still clear the 85 adjacent parts of the columns, thereby enabling the full width of the faces of the dies to operate upon such a workpiece. The capacity of the machine is therefore materially increased without any increase in 90 the cost of equipment, installation and amount of room required for placing the hammer.

The improved means for guiding and mounting the hammer head on the columns 95 are constructed as follows:

On the opposing sides of the upper parts of the columns the same are provided respectively with rabbets 15, 16, the rabbet 15 of one column, for instance the left hand 100 one, being formed on the inner front corner thereof while the rabbet 16 of the other or right hand column is formed on the inner rear corner of the last mentioned column, as best shown in Fig. 2. Each of these 105 rabbets forms an inner longitudinal bearing face, the plane of which is arranged at an angle of 20 degrees relative to the longitudinal center line of the bed plate and the columns, and a transverse outer bearing face 110

arranged at right angles to the companion inner bearing face. Secured to these bearing faces are two guides 17, 17 between which the hammer head moves vertically and is guided during this movement. These guides are adjustably secured to the longitudinal bearing faces of the rabbets so as to be capable of horizontal adjustment in a direction transversely of the hammer for the purpose of taking up wear between the coöperating surfaces of these guides and the hammer head. The preferred means for this purpose which are shown in Figs. 1 and 2 consist of clamping bolts 18 passing horizontally and transversely through the columns and through horizontally elongated openings 19 in the guides. In order to confine the hammer head against lateral displacement the coöperating surfaces of the hammer head and guides are provided with complementary coöperating vertical tongues and grooves 20, 21, 22, 23 the tongues of one of these members being adapted to enter the grooves of the other member, as shown in Fig. 2. These guides are by this means adjustably supported in the position in which they are arranged at the same angle relative to the longitudinal center line of the base and columns as the anvil block, hammer head and the dies mounted thereon.

For the purpose of holding the guides firmly in their operative position and in proper engagement with the hammer head so that the latter is guided in its vertical movements two gibs 24, 24 are employed each of which is arranged between the outer transverse side of one of the guides and the adjacent outer side or bearing face of the rabbet on the companion column. Each of these gibs preferably tapers downwardly and has its outer side which engages with the transverse side of the respective rabbet arranged vertically while its inner side is inclined and engages with the inclined outer transverse side of the companion guide. Upon forcing the gibs downwardly while the clamping bolts 18 of the guides are loose the wedging action of these gibs will cause the guides to be moved toward each other and engage fully with opposite vertical transverse sides of the hammer head so that there is no slack between the hammer head and the guides. This downward movement of each gib may be effected in various ways but preferably by the means which are shown in the drawings and which comprise an upright adjusting screw 25 on one of the guides and passing at its upper end through a lug 26 projecting inwardly from the upper end of the respective gib, and clamping nuts 27, 28 arranged on the adjusting screw 25 and bearing against the upper and lower sides of the gib lug 26, as shown in Figs. 1 and 3. After the gibs have been thus shifted for adjusting the guides into proper en-

gagement with the hammer head the same are firmly held in place by means which preferably comprise two retaining plates or clips 29 each of which is secured at one end to the outer side of one of the columns by means of a bolt 30 while its other end engages with the outer side of the companion gib. For the purpose of retaining each gib snugly in the corner of its respective rabbet and still permit this gib to move vertically for adjusting the companion guide, each of these gibs is provided on its outer side with a vertical groove 31 which receives a tongue 32 on the inner part of each retaining plate or clip, as shown in Figs. 1 and 2. These gibs are also arranged at the same angle as the guides, hammer head, anvil block and the dies so as to coöperate properly therewith. The depth of the coöperating V-shaped tongues and grooves of the guides and hammer head and the tapering form of the gibs is preferably so determined that when the gibs are removed from between the columns and the outer sides of the guides it is then possible to move the guides horizontally away from opposite transverse edges of the hammer head for disengaging the coöperating guide tongues and grooves of the last mentioned parts while the hammer head is still arranged between the guides. This is preferably accomplished by making the interlocking V-shaped tongues and grooves of the guides and hammer head of a width less than the thickness of the small ends of the tapering gibs and in practice it has been found satisfactory for this purpose to make the guide tongues one and three-eighths inches wide and the small end of the tapering gibs one and five-eighths inches in thickness. In order therefore to remove the guides for inspection, adjustment and repairs this can be accomplished without moving the hammer head above the top of the guides for this purpose and without moving the hammer head into any other particular location inasmuch as the guides can be removed while the hammer head is arranged between the same. In effecting such removal of the guides it is only necessary to first remove the gib retainer plates and then raise the gibs sufficient to disconnect the same from the adjusting screws or bolts 25 after which the gibs may be removed laterally outward from between the columns and the guides so that thereafter the latter may be backed away from opposite sides of the hammer head without disturbing the position of the latter. This is particularly advantageous inasmuch as it allows the guides to be removed without disconnecting the hammer head from the lower end of the piston rod or moving the same into any particular location with reference to the guides for permitting removal of the latter when this is necessary.

The improved means for operating the valve mechanism of the motor by movement derived from the hammer head are constructed as follows:

5 33 represents an inclined cam plate which is preferably mounted on the front side of the hammer and engages with a vertically 70
rocking or swinging cam 34 forming part of the means whereby the movement of the
10 hammer head is transmitted to the valve mechanism. As shown in the drawings this cam engages at its lower end with the cam plate and is pivotally mounted at its upper end on a horizontal rock shaft 35 which is
15 journaled in a bearing 36 on the upper arm of a shifting lever 37 which is pivoted by means of a pin 38 on the adjacent part of the right hand column. By turning the lever
20 37 the position of the cam 34 relative to the cam plate may be varied to secure the desired action of the hammer during the hammering or forging operation. The cam shaft 35 is provided with a horizontal rock arm 39 which connects with the valve rod 14 previously described so that any motion transmitted by the cam plate to the cam will be imparted to the valve mechanism which is
25 operatively connected with this valve rod.

The face of the cam plate is arranged at
30 right angles of the longitudinal center line of the bed plate and columns and parallel with the axes of the rock shaft 35 and the pivot 38 of the shifting lever 37. At its inner or rear edge the cam plate is detachably mounted upon the front side of the hammer head by providing the rear edge of the same with an upright attaching flange 40 which is of dove-tail form in cross section and of tapering form in the direction of its
35 length, being preferably smaller at its lower end and larger at its upper end. This attaching flange engages with a correspondingly shaped groove 41 in the front side of the hammer head which permits of attaching the cam plate to the hammer head by simply inserting the flange of this cam plate into the dove-tailed and downwardly tapering groove 41 in the hammer head and then driving this cam plate downwardly until its
40 flange is tight on the hammer head. By this means the cam plate may be arranged in proper relation to the parts which coöperate with the valve mechanism of the motor and its mounting on the hammer head may be
45 arranged at the same angle as the hammer and associated parts which permit of extending the workpiece beyond the gap of the hammer and still permit the full width of the dies to be employed on the same.

50 By arranging the dies, anvil block, hammer head, guides and associated parts at a sufficient angle relatively to the longitudinal center line of the bed plate and columns, a long workpiece may be extended beyond
55 the dies and still clear the edges of the

columns and permit utilizing the full width of the die faces. This is particularly advantageous when it is desired to employ hammers of this type for drawing and finishing work and also permits hammers of this 70 character to be employed for doing certain classes of ordinary heavy blacksmith's work. By thus arranging the anvil block and hammer and associated parts the necessity for using dies in which the faces are set at a 75 different angle relative to the surface of the hammer head is avoided and not only simplifies and reduces the cost of construction but also enables all of the falling parts of the hammer and the anvil to be constructed 80 on straight lines without any objectionable twists or angles in the same which are difficult to make and increase the cost of manufacture. This straight line construction which is thus possible is not confined to the 85 formation of the dies but is also present in the guides, hammer head and gibs.

By making the guides removable without disturbing the position of the hammer head it is possible to repair and adjust the guides 90 easily and expeditiously so that no undue interruption in the use of the hammer is necessary.

I claim as my invention:

1. A power hammer comprising a frame 95 having two columns provided with opposing rabbets which open forwardly their entire width, guides engaging the longitudinal sides of said rabbets, gibs arranged between the transverse sides of the rabbets and 100 the back of said guides, a hammer head movable between said guides and clamping bolts connecting said guides with said frame and passing entirely through said columns and guides. 105

2. A power hammer comprising a frame provided with opposing rabbets, guides engaging the longitudinal sides of said rabbets, gibs arranged between the transverse sides of the rabbets and the back of said guides, 110 a hammer head movable between said guides, clamping bolts connecting said guides with said frame and removable retaining plates secured to said frame and engaging said gibs. 115

3. A power hammer comprising a frame provided with opposing rabbets, guides engaging the longitudinal sides of said rabbets, gibs arranged between the transverse sides of the rabbets and the back of said 120 guides, a hammer head movable between said guides, clamping bolts connecting said guides with said frame and removable retaining plates secured to said frame and engaging said gibs, said guides and hammer being provided with complementary coöperating vertical tongues and grooves. 125

4. A power hammer comprising a frame provided with opposing rabbets, guides engaging the longitudinal sides of said rab- 130

bets, gibs arranged between the transverse sides of the rabbets and the back of said guides, and a hammer head movable between said guides, said hammer and guides being 5 provided with coöperating tongues and grooves and the distance between the back of each guide and the transverse face of the corresponding rabbet being at least equal to the depth of the coöperating tongues and 10 grooves so that said guides may be removable from said hammer while the latter is between said guides and attached to its actuating mechanism.

5. A power hammer comprising a frame 15 provided with opposing rabbets, guides engaging the longitudinal sides of said rabbets, gibs arranged between the transverse sides of the rabbets and the back of said guides, a hammer head movable between

said guides, clamping bolts connecting said guides with said frame and removable retaining plates secured to said frame and engaging said gibs, said guides and hammer being provided with complementary coöperating vertical tongues and grooves, said rabbets opening forwardly their entire widths so that said gibs are removable laterally from between said frame and guides and the distance between the back of each guide and the transverse face of the respective rabbet 30 being at least as great as the depth of said complementary tongues and grooves so as to form a clearance space which permits said guides to be disengaged laterally from said hammer while the latter is between the 35 guides.

DAVID BELL.
